UNITED STATES PATENT OFFICE.

SAMUEL J. JOYCE, OF NEW YORK, N. Y.

FIRE-ESCAPE.

SPECIFICATION forming part of Letters Patent No. 283,177, dated February 5, 1884.

Application filed April 7, 1883. (No model.)

To all whom it may concern:

Be it known that I, SAMUEL J. JOYCE, a citizen of Great Britain, residing at New York, in the county and State of New York, have 5 invented new and useful Improvements in Fire-Escapes, of which the following is a specification.

This invention relates to that class of fire-escapes in which a car adapted to support one 10 or more persons is raised and lowered to and from a window on flexible rails by means of a traction-rope, the rails having one end secured to a brace-bar for connecting them to a window, and the traction-rope being drawn 15 over a guide-pulley on such bar, while the flexible rails are combined with reels, and the traction-rope with a windlass supported on a portable frame.

This invention will be hereinafter described 20 and claimed, and is illustrated in the accompanying drawings, in which—

Figure 1 is an end view, showing the apparatus in position for use on a building. Fig. 2 is a side view thereof. Fig. 3 is a similar 25 view separate from the building, partly in section, and on a larger scale than in the previous figures. Fig. 4 is an end view, partly in section. Fig. 5 is an end view, looking in an opposite direction to Fig. 4.

Similar letters indicate similar parts.

The letter A designates the portable frame, which may be mounted on wheels B, for its 35 convenient transportation, and which forms the bearings for a shaft, C, having one end made square to receive a winch or crank for turning it.

The letter D indicates two reels placed loosely on the shaft C, and D' a windlass fixed to the shaft intermediate of the reels, so that said 40 reels may turn independently of the shaft, while the windlass shares its motion.

On the reels D are wound flexible rails F, consisting in this example of ropes, the outer 45 ends of which are connected to a bar, G, Figs. 1 and 2, which is adapted to extend across a window on the interior of a building, as shown, so that this bar may act as a brace for connecting the rails to the window.

On the windlass D' is arranged a traction- 50 rope, H, or a chain, which thence extends over a guide-pulley, I, mounted on the brace-

bar G, and is secured at the end to a car, J, having its wheels arranged in proper relation to the rails F. The body of this car is suitably constructed to support one or more persons, and may, if desired, be closed to conceal and protect the persons using it. The rails F and traction-rope H wind and unwind in opposite directions, the traction-rope being below the rails in use, as shown in Fig. 1, and 55 the motion of the reels D, containing the rails, is produced by a driving-shaft, K, the latter being geared with the reels through pinions N on the shaft, and cog-wheels O, one on each reel. Said driving-shaft, like the main shaft 60 C, is squared at one end to receive a crank, and to it is fixed a ratchet-wheel, P, engaging with a pawl, Q, to prevent the unwinding of the rails F under normal conditions, so that when the rails have been adjusted in length to 65 70 the building they remain taut.

To the main shaft C is fixed a brake-wheel, R, engaging with a brake-strap, S, the latter being attached to the frame at one end, thence extending around the brake-wheel, and having 75 its other end connected to a hand-lever, T, in a well-known manner, so that the motion of the main shaft may be controlled, with a like effect on the traction-rope.

On applying the apparatus to use, the rails 80 F are unwound and the brace-bar G is put in place, it being raised to the window by a line kept ready for this purpose. As said bar G is raised, the traction-rope H becomes unwound, due to its passage over the guide-pulley I, and the car J having been placed on the rails, it is raised to the window by rewinding 85 said rope. Then when the car has become occupied it is lowered, and so on until all the occupants of the building have escaped, when the 90 brace-bar G is withdrawn from the window.

To release the brace-bar and allow its withdrawal, it may be connected at one end to a line arranged to pass over a pulley on the upper part of the window, it thence extending 95 to the ground, so that by pulling the line the bar is displaced at one end.

What I claim as new, and desire to secure by Letters Patent, is—

1. The combination of the portable frame, 100 the shaft supported thereby, the two reels and the windlass, all mounted on the one shaft,

with the windlass between the two reels and turning with the shaft, and the reels loose thereon, the flexible car-rails arranged on the reels, the traction-rope arranged on the windlass, the car connected with the traction-rope, the brace-bar secured to the car-rails and provided with the guide-pulley, and a driving-shaft for rotating the reels on the shaft of the windlass, substantially as and for the purpose described.

2. The combination, substantially as hereinbefore set forth, of the main shaft, the windlass fixed to said shaft, the reels mounted loosely thereon, the driving-shaft geared with the reels, the ratchet-wheel fixed to the driving-shaft, and the pawl engaging the ratchet-wheel.

3. The combination, substantially as hereinbefore set forth, of the main shaft, the windlass fixed to said shaft, the reels mounted loosely thereon, the driving-shaft geared with the reels, the ratchet-wheel fixed to the driving-shaft, the pawl engaging the ratchet-wheel, the brake-wheel fixed to the main shaft, and the brake-strap acting on the brake-wheel. 20 25

In testimony whereof I have hereunto set my hand and seal in the presence of two subscribing witnesses.

SAMUEL J. JOYCE. [L. S.]
